UNITED STATES PATENT OFFICE.

GEORGE ADOLPH STEINER, OF SALT LAKE CITY, UTAH, ASSIGNOR TO STEINER SALES COMPANY, OF SALT LAKE CITY, UTAH, A CORPORATION OF UTAH.

TOWEL CABINET.

Application filed December 27, 1921. Serial No. 525,024.

To all whom it may concern:

Be it known that I, GEORGE A. STEINER, a citizen of the United States, resident of Salt Lake City, county of Salt Lake, State 5 of Utah, have invented certain new and useful Improvements in Towel Cabinets, of which the following is a specification.

The object of this invention is to provide means which will positively prevent the 10 soiled towel roll from being unwound and also to defeat any attempt to prevent the soiled portion of the towel from winding up on its proper roll.

A further object is to provide means at 15 the lower front portion of the cabinet to prevent anyone from reaching in under the clean towel roll and unwinding it or in any way interfering with its normal feeding movement.

20 A further object is to provide means at the lower rear portion of the cabinet to prevent anyone from reaching up in the rear of the clean towel roll and operating it or in any way interfering with its normal movement.

Other objects of the invention will appear from the following detailed description.

The invention consists generally in various 30 constructions and combinations, all as hereinafter described and particularly pointed out in the claims.

In the accompanying drawings forming part of this specification,

Figure 1 is a vertical sectional view 35 through a towel cabinet embodying my invention,

Figure 2 is a vertical sectional view on the line 2-2 of Figure 1, looking toward the rear of the cabinet,

40 Figure 3 is a detail view of the feed roll chain drive, showing the means for preventing backward movement of the drive chain and sprockets.

In the drawings, 2 represents the wall of 45 the cabinet, having a door 3 at the front thereof and guides 4 and 5 in the side walls of the shafts 6 and 7 of the towel rolls 8 and 9. When the door 3 is opened, the slots or guides 4 and 5 are exposed to allow the convenient insertion of the roll shafts therein 50 or their removal therefrom. The clean towel roll is preferably placed in the lower guideways in the cabinet and the inner portions of both of the guideways are preferably turned downwardly in a vertical position, substan-

tially so that when the shafts are inserted therein the rolls carried thereby will be supported by gravity. The roll 8 rests upon a feed or control roll 10 which has a shaft 11 mounted in the side wall of the casing and is 60 connected by a bolt or chain 12 with the other control or feed roll 13 that is mounted upon a shaft 14. The surface of the roll 10 is preferably covered with sandpaper or rubber, and the clean towel roll rests by gravity 65 thereon with sufficient friction to revolve and transmit its movement through the belt or chain 12 to the other feed roll above which is the soiled towel roll 9.

I prefer to wrap the feed roll 13 with a 70 belt 15 having a series of studs 16 therein which contact with the surface of the soiled towel roll. When the cabinet is operated properly, the soiled towel roll will ride easily on the ends of the studs or wires in 75 the periphery of the roll 13, but if anyone should attempt to pull the soiled towel roll backward, or attempt to hold it from revolving to roll up the towel thereon while the clean towel is being fed from its roll, then 80 the ends of the wires in the belt 15 will stick into the roll of soiled towel and hold it firmly and prevent backward movement thereof.

The lower portion of the casing has a 85 transverse brace 17 and in front of this brace is an opening 18 through which the clean portion of the towel depends, and I prefer to arrange a bracket 19 on the lower portion of the door to project into this space 90 18 and prevent anyone thrusting the hand up under the cabinet and unrolling the clean towel. This bracket also compels the user to exert a perpendicular downward pull on the clean towel, sufficient pressure being obtained thereby to operate the feed roll 10 95 and from it the roll 13. This pressure also prevents the clean roll from slipping in its operation and the downward pull thereon increases the friction between it and the feed 100 or control roll beneath.

At the rear of the cabinet is a passage 20 through which the soiled portion of the towel passes and a shield 21 having a ledge or shelf at its lower end is pivoted at 22 105 and has the function of preventing the hand from being thrust up under the cabinet in the rear of the roll of clean toweling and unrolling it or in any way interfering with the proper operation of the rolls.

At the top of the cabinet I prefer to provide a shield 23 pivoted at 24 in the rear and near the soiled towel roll and projecting upwardly above the top of the roll and having an upper edge over which the soiled towel passes to its roll beneath. Arms 25 are provided at the upper end of the shield and extend above the surface over which the soiled towel passes, forming guides to prevent the towel from coming in contact with the walls of the cabinet. A latch 26 is mounted on the side walls of the cabinet and has the function of preventing the shield from tilting forward beyond a predetermined point.

It will be noted that both the clean and soiled towel rolls rest by gravity upon the feed or control rolls beneath.

I claim as my invention:

- 20 1. A towel cabinet comprising a casing, clean and soiled towel rolls therein, a shield pivoted at its bottom in the rear of the cabinet and over which the soiled towel is guided; a releasable latch for holding the shield in its rearward position, a shield pivoted to the casing near its bottom, said towel in passing over one roll to the other being behind said shields, said last mentioned shield having an angular extension, a bracket at
- 25 30 the bottom of the casing which coacts with said angular extension to prevent access

through the bottom of the casing to the towel roll.

2. A towel cabinet comprising a casing, clean and soiled towel rolls mounted therein, feed rolls for said towel rolls having a driving connection between them, the soiled towel feed roll having pins in its peripheral surface, the soiled towel extending upwardly in the back of the casing, a shield 40 angular in form mounted in the upper portion of said casing and having a horizontal and vertical part between which and the rear of the casing the soiled towel is directed, the horizontal part of the shield preventing 45 access through the lower part of the casing to the soiled towel roll, a latch for the shield which when released allows the shield to be tilted forwardly and the towel passed back of the shield and extended to the soiled 50 towel roll and feed roll where it may be held by said pins so that the shield may be pushed back and smooth the towel and the shield latched in its backward position, a second shield in the casing near its bottom, 55 said towel in passing from one roll to the other being behind both said shields.

In witness whereof, I have hereunto set my hand this twentieth day of December, 1921.

GEORGE ADOLPH STEINER.
